UNITED STATES PATENT OFFICE

132,629

DESIGN FOR A NEGATIVE LOADER

Frank A. Mortimer, Seattle, Wash.

Application January 30, 1942, Serial No. 105,528

Term of patent 7 years

To all whom it may concern:

Be it known that I, Frank A. Mortimer, a citizen of the United States, residing at Seattle, in the county of King, in the State of Washington, have invented a new, original, and ornamental Design for a Negative Loader, of which the following is a specification, reference being had to the accompanying drawing, forming part thereof.

Figure 1 is a perspective view of the forward

and side portions of the negative loader showing my new design, and

Figure 2 is a perspective view of the rear and side portion of the negative loader as though taken from an upper level.

I claim:

The ornamental design for a negative loader, substantially as shown.

FRANK A. MORTIMER.
